CUTTING MACHINE

Homer C. Warner and Charles H. Schurr, Cleveland, Ohio, assignors to The Lees-Bradner Company, Cleveland, Ohio, a corporation of Ohio

Application October 6, 1931, Serial No. 567,276

17 Claims.

(Cl. 90—4)

This invention relates to cutting machines, and is particularly applicable to hobbing machines, milling machines and the like.

An object of the invention is to provide an improved machine in which a number of independent units may be conveniently grouped together and attended by a single operator.

Another object of the invention is to provide an improved machine having few and simple parts.

Another object of the invention is to provide an improved machine unit in which the cutting operations may be carried on automatically, and during such operation the machine unit will be removed from in front of the operator, so that he may devote his attention to another similar machine.

Another object of the invention is to provide an improved machine which will be economical of manufacture and operation.

Another object of the invention is to provide an improved machine which will be speedy in production and simple in operation.

Other objects will hereinafter appear.

The invention will be better understood from the description of one practical embodiment thereof illustrated in the accompanying drawings, in which:

Figure 1 is a side elevational view, with parts broken away or in section, of an assembled machine having a number of machine units designed for hobbing gears;

Figure 2 is a vertical sectional view of one unit taken on the line II—II of Figure 1;

Figure 3 is a horizontal sectional view taken on the line III—III of Figure 1;

Figure 4 is a horizontal sectional view taken on the line IV—IV of Figure 1;

Figure 5 is a sectional view taken on the line V—V of Figure 4; and

Figure 6 is a fragmentary elevational view of the gears constituting the differential and which appear in section in Figure 5.

The apparatus shown comprises a stationary bed 1 upon which and adapted to rotate about a vertical axis is mounted a base or table 2. The central portion of the bed extends upwardly through the center of the base, as indicated at 3, while the base has a downwardly extending central flange 4 fitting within the hollow of the bed and surrounding the projection 3.

The exterior of the bed is formed with an upturned flange 5 forming an annular trough 6 for the reception of cooling fluid and chips.

Keyed to the downwardly projecting flange 4

of the base is a worm wheel 7 with which meshes a worm 8 carried by a horizontal shaft 9 journaled within the bed and connected by means of a clutch 10 with an electric motor 11 or other driving means, so that the motor, through the worm and worm wheel, causes the base to rotate upon the bed.

An upwardly extending tubular column 12 is secured to the central projection 3 of the bed, as by bolts or screws 13 and serves to support an insulating ring 14 carrying a plurality of collector rings 15 connected by suitable conductors 16 with a source of electric current. This column has no other function than the supporting of the collector rings or commutator mechanism, and is shown as extending to the top of the machine merely to support the collector rings in a convenient and accessible position. Obviously, these might be suspended from the ceiling or mounted elsewhere, as directly upon the top of the central projection of the bed.

Secured upon the upper surface of the base or platform 2 are a number of independent machine units, each shown as constituting in effect a hobbing machine, separate from and independent of each of the others.

Each machine unit consists of a main frame 17 having at its bottom a horizontal flange 18 secured upon the upper surface of the base as by screws 19 and provided on its top with a substantially horizontal flange 20 on which is supported an electric motor 21 having conductors 22 connected to brushes 23 supported on an insulating bracket 24, and engaging the collector rings upon the central column.

The motor shaft is provided with a grooved pulley 25 which drives V-belts passing over a second grooved pulley 26 mounted upon a horizontal shaft 27 journaled in a housing 28 secured to the upper side of the flange 20. The inner end of the shaft has keyed to it a bevelled gear 29 meshing with a bevelled gear 30 secured to the upper end of a vertical shaft 31 journaled in the horizontal flange 20, and in a housing or bracket 32 secured to the frame of the unit.

Formed upon the frame are two pairs of vertical ways 33 and 34 on one pair, 33, of which is slidably mounted a carriage 35 having formed upon it horizontal ways 36, and in these horizontal ways a slide or carrier 37 is arranged for translation.

Upon the carriage is journaled a horizontal shaft 38 having at one end a bevelled gear 39 meshing with a bevelled gear 40 splined to the

vertical shaft 31, these two bevelled gears being housed within a projection 41 of the carriage.

The horizontal shaft 38 is itself splined to another horizontal shaft 42 journalled upon the 5 slide, and is provided at its end with a bevelled gear 43 meshing with a bevelled gear 44. The last mentioned gear is secured to a shaft 45 carried by a head 46 adjustably connected to the slide and arranged to be adjusted angularly 10 about the axes of the horizontal shafts 38 and 42, and the head carries, within a housing-like extension 47, change gears 48 by which a spindle 49, also journalled in the head, may be driven from the vertical shaft at any selected speed. 15 Upon this spindle is secured a hob or cutting tool 50.

Preferably the carriage is fed downwardly, and a counterweight is provided to compensate for the weight of the carriage, being connected 20 thereto as by cables or a chain passing from sheaves supported upon the upper portion of the frame.

As above mentioned, the lower end of the vertical shaft 31 is journalled within a bracket 32 25 secured to the frame, and within this bracket the shaft has keyed to it a bevelled gear 51 meshing with a bevelled gear 52 upon a horizontal stub shaft 53 also journalled in the bracket, and provided at its other end with a spur 30 pinion 54 which drives a spur pinion 55 secured to the end of a horizontal shaft 56.

The end of the horizontal shaft adjacent the pinion is journalled in the bracket, while the shaft itself extends through a housing 57 in 35 which it is also journalled, being provided on its outer end with a change gear 58 meshing with a second change gear 59 upon a parallel shaft 60 also journalled in this housing.

The last mentioned shaft has formed upon it, 40 within the housing 57, a skew gear 61 and a worm 62. The worm meshes with a worm wheel 63 rotatably mounted upon a spindle 64 supported in bearings 65 and 66 within the housing.

Keyed to the worm wheel is a gear 67 with 45 which mesh pinions 68 constituting part of a spur differential mechanism, these pinions in turn meshing with other pinions 69 of a differential mechanism, which latter engage a gear 70 keyed to the spindle. The two sets of pinions are journalled within a drum-like ring 71 having on its exterior gear teeth engaged by the conjugate teeth of a gear 72 formed upon a sleeve 73 journalled in the housing. Passing through the sleeve is a rod 74 secured at its upper end to the carriage as by screws, and provided on its exterior with a generally helical groove or land 75. Attached to the lower end of the sleeve is a nut 76, conveniently made by casting bearing metal about the rod 74, and having a land or groove 60 engaging groove or land 75 of the rod, so that as the carriage is moved upwardly or downwardly the sleeve is rotated, and this motion is transmitted to the differential mechanism, and so causes a variation of the rotation of the spindle 65 in proportion with the upward and downward movement of the carriage.

Different rods, each with its conjugate nut, will be supplied for helical gears of different leads. If it is desired to cut a spur gear, a rod 70 having a groove parallel to its axis may be used. However, a rod having a helical groove might be used by being secured to the housing 57, or the worm wheel 63 might be secured to the work spindle, and obviously, if it is not desired to use 75 the machine to cut helical gears, the differential

mechanism may be entirely omitted, the worm wheel being permanently secured to the spindle.

A hood 77 is attached to the upper end of the spindle and overlies the upper end of the housing, so that dirt, chips, and lubricant will be 5 excluded from the interior of the housing.

The spindle above referred to is intended to hold a center, arbor, or the like by which the work is supported, and to rotate this in proper relation to the rotation of the tool upon the 10 spindle 49 above described.

Mounted upon guideways 34 is a tailstock 78, shown as provided with a center 79, and arranged to support the upper end of the work, its arbor, or the like. The mechanism for lowering 15 the tailstock into supporting engagement with the work, or raising it to facilitate the removal or replacement of the work, is shown as a rack 80 upon the frame, a pinion 81 engaging the rack and carried by the tailstock, and a crank 82 for 20 rotating the pinion.

A transverse shaft 83 extends through the housing 57 above described and through a housing 84 at the other side of the frame, being journalled within both these housings and provided 25 adjacent one end with a skew gear 85 meshing with skew gear 61. The other end of the shaft is provided with a change gear 86 meshing with a change gear 87 upon a parallel shaft 88 journalled in housing 84 and provided on the interior 30 thereof with a worm 89.

This worm engages a worm wheel 90 carried by a vertical shaft 91 journalled within the housing. This shaft is provided with a drum 92, upon the cylindrical surface of which is a cam groove 93, in which is situated a follower roller 94 secured to a vertically slidable bar 95, which, in turn, is connected by means of a reversely threaded screw 96 to the carriage 35, so that the latter may be moved up and down by the rotation of the drum. The reversely threaded screw is, of course, provided for adjustment between the bar and carriage.

Upon the upper surface of the drum is formed a cam groove 97 within which runs a roller 98 secured to a bell-crank lever 99 pivoted at 100 to the housing and having its outer end bifurcated and adapted to receive the trunnions 101 of a ring 102 fitting within a circumferential groove in the exterior of the shaft 103. Also 50 within the groove of shaft 103 is a compression spring 104 bearing at one end upon the ring and at the other upon a shoulder 105 formed on the shaft. This is to permit the motion of the bell-crank lever as it is actuated by the cam 55 while also permitting the use of a fixed stop which limits the motion of the slide.

The inner end of the shaft is threaded and the threads engage a worm-wheel-like pinion 106 keyed to a vertical shaft 107 journalled within bracket 32 and carriage 35.

The upper end of the vertical shaft 107 has a pinion 108 splined to it, the pinion meshing with rack teeth 109 upon the slide, so that as the bell crank is moved by the cam 97, the rod or shaft 103 is reciprocated axially, turning the vertical shaft and moving the slide upon its ways by means of the rack. The end 110 of the rod is shaped to be engaged by a crank or handle so that the rod may be rotated to adjust the position of the carrier upon the carriage independently of the cam, a scale being shown upon the rod for this purpose.

A stop 111 is rigidly carried by the slide and is arranged to engage the end of a set screw 112 75

threaded through a bracket 113 fixed to the carriage.

The collector rings are interrupted, as indicated at 114, so that when each unit reaches the position in front of the operator, its motor will be stopped and all parts of the unit will be stationary while he is removing one piece of work and inserting another. During this period, the rotation of the base upon the bed will continue and the remaining units will also continue in their operation, or clutch 10 may be operated to stop the rotation of the base while permitting the other units to continue their operation.

The frame of each of the machine units is recessed, as indicated at 115, so that the cutter head 46' of an adjacent unit may project within the frame, as indicated in dotted lines in Figures 2 and 3 of the drawings. By so recessing the frame, it is possible to position a number of units compactly upon a relatively small table, it being possible when, for instance, eight units are used to arrange these so that the shafts 38 and 56 are not radial of the table, but extend in lines tangent to a circle concentric therewith, and the cutter heads of each machine unit are received within the recesses of an adjacent unit, decreasing the necessary diameter of the table substantially ten percent.

The operation of the device is as follows: The gears 48, 58 and 59 are chosen so that the relative rotations of the work and cutter spindles are in any desired relation. Gears 86 and 87 are provided to rotate the cams at a suitable speed. The cutter head is angularly adjusted by loosening the screws and moving the head 46 upon the slide 37. If the machine is being used to cut helical gears, a suitable rod 74 and nut 76 are provided, the rod being connected to the carriage and the nut to sleeve 73.

Having adjusted the above parts, the operator engages the clutch 10 so that the motor 11 causes the base to revolve upon the bed, and as each unit passes beyond his station, its brushes 23 engage the collector rings, and its motor starts to drive the moving parts. This motion is transmitted through the vertical shaft 31, gears 39 and 40, horizontal shafts 38 and 40 and gears 43, 44 and 48 to the cutter, and also through gears 51, 52, 54, 55, 58, 59, 62 and the differential mechanism to the work spindle and through gears 61, 85, 86, 87, 89 and 90 to the cam drum.

As soon as the drum starts its rotation, roller 94 and by it the rod 95 and the carriage are moved downwardly, feeding the cutter from end to end of the work. Simultaneously, through the bell crank 99, rod 103, worm wheel 106, shaft 107, pinion 108 and rack 109, the slide is fed inwardly as the roller 98 is moved into the concentric portion of the cam groove, during which time the motion of the slide is arrested by the stop 111 and spring 104 is somewhat compressed.

After this, the cutter will be held in its innermost position until the roller 98 reaches the end of this portion of the groove, at which time it will actuate the parts to retract the slide. At the same time, the carriage will be raised by the cylindrical cam 93. The brushes of the unit having by now reached the gap 114 in the collector rings, the motor is stopped and the operator may remove the work and replace it with another piece.

While the feeds both down and inwardly are shown as operating only once in each revolution of the drum, it will be obvious that the cutter 75 might be fed in something less than full depth

and advanced downwardly throughout the length of the work, then retracted and brought upwardly and fed into full depth and downwardly again, so that during a single revolution of the drum both a roughing and a finishing cut will be taken. Also, the feed might be from the bottom to the top of the work piece, instead of as shown, from the top to the bottom.

While we have described the illustrated embodiment of our invention in some particularity, obviously many others will readily occur to those skilled in this art, and we do not therefore limit ourselves to the precise details shown and described herein, but claim as our invention all embodiments, variations and modifications coming within the scope of the appended claims.

We claim:

1. A machine comprising a frame, a spindle journaled thereon, guideways on said frame parallel to said spindle, a carriage movable on said guideways, guideways on said carriage normal to said first mentioned guideways, a slide movable on said second mentioned guideways, a spindle carried by the slide, gearing between said spindles including a differential, a gear engaging a part of said differential journaled on said frame, a nut secured to said gear, and a splined shaft secured to said carriage and engaged by said nut to rotate said gear upon movement of the carriage.

2. A machine tool comprising a tool spindle and work spindle, one of said spindles being movable in two directions relative the other, a cam moving said spindle in one direction, a second cam moving said spindle in the other direction, a stop limiting the motion of said spindle in the first mentioned direction, resilient means interposed between said spindle and the first mentioned cam and gearing between said spindles and cams causing them to rotate at predetermined relative velocities.

3. A machine tool comprising a tool spindle and work spindle, one of said spindles being movable in two directions relative the other, a cam moving said spindle in one direction, a second cam moving said spindle in the other direction, a stop limiting the motion of said spindle in the first mentioned direction, resilient means interposed between said spindle and the first mentioned cam, and differential mechanism varying the relative velocity at which the spindles are rotated and actuated by the movement of said spindle in one direction.

4. A machine tool comprising a tool spindle and a work spindle, one of said spindles being movable in two directions relative the other, cams for imparting motion to said spindle in both said directions, a stop limiting the motion of said spindle in one direction, resilient means interposed between said spindle and one cam, gearing between said spindles causing them to rotate at a predetermined relative velocity, and differential mechanism varying the relative velocity at which the spindles are rotated and actuated by the movement of said spindle in the direction of the axis of the other.

5. A machine tool comprising a frame, a carriage slidable thereon, a slide slidably carried by said carriage, a spindle journaled on said slide, a second spindle journaled on said frame, gearing between said spindles, two cams actuated by said gearing, connections between one cam and said carriage, and connections between the other cam and said slide.

6. A machine tool comprising a frame, a car-

- riage movable thereon, a slide movably carried by said carriage, a spindle journalled on said slide, a second spindle journalled on said frame, gearing between said spindles, two cams actuated by said gearing, connections between one cam and said carriage, connections between the other cam and said slide, differential mechanism interposed in the gearing between the spindles, and a connection between a part of said differential and 10 said carriage. 5
7. A machine tool comprising a frame, a slide thereon, a spindle journalled on said frame, a cam, gearing between the spindle and cam, a cylindrical rod reciprocated by the cam, a thread 15 in said rod, a worm wheel meshing with said thread, operative connections between said worm wheel and slide, and means for rotating said rod. 15
8. A machine comprising a frame, a work spindle journalled thereon, guideways on said frame 20 parallel to said work spindle, a carriage movable upon said guideways, guideways on said carriage normal to said first mentioned guideways, a slide movable upon said second mentioned guideways, a cam for moving said carriage, a cam for 25 moving said slide, and gearing between said cams and said spindles. 25
9. A machine comprising a frame, bearings carried thereby in fixed position, a spindle journalled in said bearings, guide-ways on said frame 30 parallel to the axis of said spindle, a carriage movably supported on said guide-ways, guideways on said carriage normal to said first mentioned guide-ways, a slide movably carried on said second mentioned guide-ways and provided with 35 bearings, a second spindle in said second mentioned bearings, gearing between said spindles including differential mechanism, and operative connections between said carriage and said differential mechanism. 35
- 40 10. A machine tool of the class described comprising a frame, bearings carried thereby in fixed position, a spindle journalled in said bearings, guideways on said frame parallel to the axis of said spindle, a carriage movably supported on 45 said guide-ways, guideways on said carriage normal to said first mentioned guideways, a slide movably carried by said second mentioned guideways, a shaft journalled on the slide, gearing between the spindle and the shaft, drive means associated with said gearing, a head secured to the 50 slide angularly adjustable relative thereto, a spindle journalled in the head, and gearing between said last mentioned spindle and said shaft and carried by said head. 50
- 55 11. A hobbing machine comprising a frame, a spindle journalled thereon, guideways on said frame, a carriage movable on said guideways, guideways on said carriage, a slide movable on said second mentioned guideways, a spindle carried by the slide, gearing between said spindles and including a differential, a gear engaging a 60 part of said differential journalled on said frame, a nut secured to said gear, and a splined shaft movable with said second mentioned spindle and engaged by said nut to rotate said gear upon movement of said last mentioned spindle. 60
- 65 12. A hobbing machine comprising a tool spindle and a work spindle, one of said spindles being movable in two directions relative the other, gearing between said spindles, feed means operated by said gearing moving said last mentioned spindle in one direction, second feed means operated by said gearing moving said last mentioned spindle in the other direction, a stop limiting the motion of said spindle in the first mentioned direction, and resilient means interposed between said spindle and said first mentioned feed means. 10
13. A hobbing machine comprising a frame, a carriage slidable thereon, a slide slidably carried by said carriage, a spindle journalled on said slide, a second spindle journalled on said frame, gearing between said spindles, feed means actuated by said gearing, connections between said feed 15 means and said carriage, second feed means actuated by said gearing, and connections between said second feed means and said slide. 15
14. A hobbing machine comprising a frame, a carriage slidable thereon, a slide slidably carried by said carriage, a spindle journalled on said slide, a second spindle journalled on said frame, gearing between said spindles, feed means actuated by said gearing, connections between said feed 20 means and said carriage, second feed means actuated by said gearing, and connections between said second feed means and said slide. 20
15. A hobbing machine comprising a frame, fixed bearings thereon, a spindle journalled in said bearings, guideways on said frame, a carriage movable upon said guideways, guideways on said carriage, a slide movable upon said second mentioned guideways, a spindle journalled on said slide, feed means operatively connected to said carriage, second feed means operatively connected to said slide, and gearing between both said feed means and said spindles. 25
16. A hobbing machine comprising a frame, fixed bearings thereon, a spindle journalled in said bearings, guideways on said frame, a carriage movable upon said guideways, guideways on said carriage, a slide movable upon said second mentioned guideways, a spindle journalled on said slide, feed means operatively connected to said carriage, second feed means operatively connected to said slide, and gearing between both said feed 30 means and said spindles, differential mechanism interposed in the gearing between the spindles and a connection between a part of said differential and said slide. 30
17. A hobbing machine comprising a frame, bearings carried thereby in fixed position, a spindle journalled in said bearings, guideways on said frame, a carriage movably supported on said guideways, guideways on said carriage, a slide movably carried on said second mentioned guideways and provided with bearings, a second spindle in said second mentioned bearings, gearing between said spindles including differential mechanism, and operative connections between the differential and a part movable with said second 40 mentioned spindle. 40
